United States Patent Office

Des. 217,490
Patented May 5, 1970

217,490

TORTILLA KEEPER OR THE LIKE

James B. Swett, Barrington, and Robert F. Bateman, Providence, R.I., assignors to Dart Industries Inc., a corporation of Delaware

Filed Mar. 3, 1969, Ser. No. 15,987

Term of patent 14 years

Int. Cl. D7—01

U.S. Cl. D44—15

FIG. 1

FIG. 2

FIG. 3

FIG. 5

FIG. 1 is a perspective view of a tortilla keeper showing our new design;

FIG. 2 is a top plan view;

FIG. 3 is a bottom plan view;

FIG. 4 is a side elevational view; and

FIG. 5 is an end elevational view.

We claim:

The ornamental design for a tortilla keeper or the like, substantially as shown.
